SWITCH ASSEMBLY FOR A TELEPHONE SUBSET
James F. Kessler, Webster, N. Y., assignor to General Dynamics Corporation, Rochester, N. Y., a corporation of DelawareApplication November 14, 1956, Serial No. 622,220
7 Claims. (Cl. 179—165)

My invention relates to telephone subsets and more particularly to telephone subsets having manually operable auxiliary contact sets in addition to the conventional hookswitch contact sets.

In the past, it has been the practice to provide an auxiliary contact set on a telephone subset for such purposes as cutting off extension stations, thereby insuring against the possibility of intrusion while the subset is in use. An example of such a subset is found in Patent 2,273,530—King, where the auxiliary hookswitch actuating plunger is so positioned on the subset that the plunger engages the handset when the latter is on the subset cradle in the normal, on-hook position. Such an arrangement is advantageous because it insures the restoration of the auxiliary contact set to its normal condition when the subset is not in use. For this reason it is desirable to preserve the handset-actuated feature of such auxiliary contact set plunger. However, in telephone subsets of the type shown in Patent 2,749,395, entitled "Telephone Subset," Droe and Kucharski, issued June 5, 1956, where the main body of the hookswitch assembly is laterally removed from the cradle pieces by a substantial distance, the control of auxiliary contacts by a plunger of the type taught by King becomes impractical if the practice of mounting auxiliary contact sets on the central bracket in the manner disclosed by Droe and Kucharski is to be followed.

Accordingly, it is an object of my invention to provide a new and improved auxiliary contact set mounting method.

Another object of my invention is to provide a new and improved method for actuating such auxiliary contact sets.

Another object of my invention is to provide an auxiliary contact set which may be included or omitted from a particular subset without modifying the hookswitch assembly.

I accomplish these and other objects in the manner described in the following paragraphs. For a better understanding of my invention, reference is made in the following paragraphs to the drawings attached to and forming a part of the present specification, and in which:

Fig. 1 shows a partial view of an assembled telephone subset;

Fig. 2 shows a cross-section taken through a part of the assembled subset; and

Fig. 3 shows a partially exploded view of a cradle and plunger piece bearing an auxiliary contact set.

Referring to Fig. 1, my invention may be practiced in a telephone subset of the type described in the aforementioned Droe and Kucharski patent. The subset comprises a pedestal portion including shell 1 and a handset including transmitter portion 5, receiver portion 6, and the handle portion 7 which interconnects portions 5 and 6. The pedestal portion also includes base 2 on which the support 12 is fixed. Hookswitch contact set 9 is secured to support 12 by screws such as 11. The contact bearing end of the hookswitch contact springs within set 9 are controlled by U-shaped hookswitch arm 5 which is pivotally attached to bracket 12 by pin 6. Arm 13, which is also fixed to base 12 by the contact set securing screws such as 11, carries one end of biasing spring 10. The other end of spring 10 is attached to arm 5 so that spring 10 urges arm 5 in an upper direction around pivot pin 6.

2

Combined cradle and plunger pieces 4 and 4a are pivotally attached to the ends of the legs of arm 5 by a pin such as 8. The upper, handset-receiving portions of the plunger pieces including surfaces 14 and 14a emerge through openings in shell 1 when the latter is in its assembled position on base 2 in the manner shown in Fig. 2. While the subset is not in use, portion 7 of the handset is laid across surfaces 14 and 14a of the plunger pieces. The weight of the handset is sufficient to overcome the tension in biasing spring 10, so that the current plunger pieces depress arm 5 which in turn causes contact set 9 to assume its normal position. When the handset is removed from cradle pieces 4 and 4a, the tension in biasing spring 10 moves arm 5 in an upward direction for a distance sufficient to operate the springs in contact set 9.

The present invention relates to the mounting of and apparatus for operating an auxiliary contact set. The auxiliary contact set includes springs such as 15 and 15a mounted on one of the plunger pieces such as 4. At the 20 end of mounting the auxiliary contact set, grooves of rectangular cross-section are formed on opposite sides of the plunger piece 4. The grooves, of uniform depth, follow a nonlinear path across the sides of the plunger piece and are parallel to each other throughout their 25 length. One end of each groove terminates at an edge of the plunger piece 4. The other end of the groove terminates in an edge of plunger piece 4 formed at an opening or window 4c passing through plunger piece 4 from one side surface to the other. Both the groove and window are so positioned on plunger piece 4 that they lie entirely within the shell 1 when plunger piece 4 is in its raised (operated) position. The springs such as 15 and 15a which are included in the auxiliary contact set are substantially the same width as the grooves and are shaped 30 along a portion of their length to be received within the grooves. Of the remaining portions of each spring, one end emerges from the block to receive an externally connected wire or wires such as 24a or 24b while the other end lies wholly within the aforementioned window. The 35 end lying within the window is offset from the remainder of the spring toward the center of plunger piece 4 and bears a contact such as 16.

The depth of the groove in the sides of plunger piece 4 is sufficient to allow the outward-facing surfaces of the 45 springs 15 and 15a as well as the presently described fastening means and plunger assembly to lie wholly within the boundaries of the plunger piece 4 defined by the side surfaces of the plunger piece. The springs are secured to plunger piece 4 (which is made of insulating material) 50 by a single fastening means including fiber insulator 20. Insulator 20 is inserted through an aperture passing through plunger piece 4 and which intersects the bottom of the spring-receiving grooves. Insulator 20 also passes through corresponding openings in springs 15 and 15a. 55 Screw 21 is then inserted through insulator 20. The springs are further insulated from each other by placing fiber washer 22 over the threaded end of screw 21 and insulator 20. The contact assembly is then fixed in position by running nut 23 onto the threaded portion of the 60 screw.

By making the groove and spring widths substantially 65 equal it is possible to fix the springs relative to each other so that the contacts 16 of each spring engage when the springs are deflected inwardly, in the manner to be described, by the use of the above-described single fastening. The use of nonlinear spring-receiving grooves in cradle piece 4 prevents interference between plunger piece 4 and shell 1 at the straight, thin wall formed in shell 1 at the 70 plunger piece receiving aperture because at least a portion of each side surface of the plunger 4 is presented to the aforementioned thin wall of the shell as the plunger

piece is passed through the aperture during the assembly of the subset.

A plunger assembly including actuating plunger 18 is provided for controlling the auxiliary contact set. Plunger 18 passes through vertical openings in cradle piece 4 and between springs 15 and 15a. An enlarged, insulated cam portion 17 is fixed to plunger 18. When plunger 18 is in its normal, depressed position, the rounded lower section of portion 17 engages springs 15 and 15a forcing them apart, so that the contacts 16 of springs 15 and 15a are disengaged from each other. As will be described, plunger 18 may be manually raised to disengage portion 17 from springs 15 and 15a so that tension within springs 15 and 15a causes the springs to be deflected toward the center of plunger piece 4. Thus contacts 16 of the auxiliary springs engage when plunger 18 is raised to its operated position. While I show a single set of make-break contacts as the preferred embodiment of my invention, it will be understood by those skilled in the art that it is possible to provide spring combinations of more than one set and type by modifying the above-described structure.

In order to make it possible for plunger 18 to be manually operated, a handle portion 19 is fixed to the upper end of plunger 18. When plunger 18 is in its normal or lower position, handle 19 lies partially within a recess in surface 14 of plunger piece 4, and is depressed below surface 14 for a distance sufficient to make the upper surface of handle 19 substantially coplanar with the handset-receiving surface 14. Thus, with plunger 18 in normal position, the handset may be placed in the plunger piece without interfering with the position of the handle portion 19. The recess in which the handle portion is depressed opens into the sides of plunger piece 4. Handle portion 19 is of sufficient width to overhang the side surfaces of plunger piece 4. The user of the subset may therefore grasp the overhanging portions of plunger handle 19 between his thumb and forefinger to manually raise the plunger 18 from the normal lower position. When plunger 18 is in its raised or operated position, the weight of the handset, when placed on handle portion 19, is sufficient to cause enlarged portion 17 to force apart springs 15 and 15a, so that handle 19 and plunger 18 can again be restored to their normal lower positions when the handset is hung up. In this manner, the aforementioned restoration of the auxiliary contact set to its normal condition when the subset is not in use is accomplished.

While I have shown and described a particular embodiment of my invention, it will be obvious to those skilled in the art that changes and modifications may be made without departing from my invention in its broader aspect. I, therefore, intend in the appended claims to cover all such changes and modifications as fall within the true spirit and scope of my invention.

What is claimed is:

1. In a contact assembly for use in a telephone subset, a plunger piece comprising a block of insulating material for receiving a telephone handset, said block having sides and an opening passing through said block from one of said sides to the other, a set of contact springs carried by said block, a portion of each of said springs extending into said opening, and means for actuating said spring set, said spring portions and said actuating means lying wholly within borders of said block defined by said walls, whereby said spring portions and said actuating means are non-interfering with other components in said subset which are adjacent to said sides.

2. The contact assembly set forth in claim 1 wherein grooves in said sides terminate in said opening, and having in addition certain other portions of each of said springs received within said grooves, said certain other portions lying wholly within the boundaries of said block defined by said side surfaces.

3. The contact assembly set forth in claim 1 wherein

grooves in said sides having a rectangular cross-section terminate in said opening, and having in addition certain other portions of each of said springs of rectangular cross-section and of substantially the same width as said grooves received within said grooves, said certain other portions of said springs lying wholly within the boundaries of said block defined by said sides.

4. The contact assembly set forth in claim 1 wherein grooves in each of said sides, substantially parallel throughout their length, terminate in said opening, and having in addition certain other portions of each of said springs received within said grooves, and a single fastening means passing through an opening in said block intersecting the bottoms of said grooves for securing said springs, whereby said single fastening means is effective for preventing lateral movements of said springs and said springs are restrained against rotational movement relative to said block and each other by the walls of said grooves.

5. The contact assembly set forth in claim 1 wherein grooves in said sides substantially parallel throughout their length follow a curved path across a part of said sides and terminate in said opening, and certain other portions of each of said springs received within said grooves, said certain other portions lying wholly within the boundaries of said block defined by said surfaces, whereby interference between said grooves and narrow straight line surfaces within said subset which are adjacent to said plunger piece do not interfere with said grooves as said plunger piece is moved with respect to the straight line narrow surfaces.

6. In a telephone subset comprising a shell, a hook-switch assembly including a contact set within said shell, a combined cradle-plunger piece attached to said hook-switch assembly for actuating said contact set, and a handset, wherein a portion of said plunger piece emerges from said subset through an aperture in said shell, the combination comprising: a set of auxiliary contacts, an actuating plunger passing through a first opening in said plunger piece having an enlarged section for controlling said auxiliary contact set, said enlarged portion and certain portions of each of said springs lying within a second opening passing through said cradle piece, grooves of uniform depth in said sides following a nonlinear path across said sides and terminating in said second opening, certain other portions of each of said springs received within said grooves, said certain other portions lying wholly within boundaries of said block defined by said sides, and single fastening means passing through a third opening through said block intersecting the bottoms of each of said grooves for securing said springs to said plunger piece, whereby said spring portions and said actuating means are non-interfering with other components in said subset which are mounted adjacent to said sides and narrow straight surfaces of apparatus mounted adjacent to said sides are non-interfering with said plunger piece as said plunger piece is moved vertically to operate said hookswitch assembly.

7. In a contact assembly for use in a telephone subset, a plunger piece comprising a block of insulating material for receiving a telephone handset, said block having sides and a top surface, a set of contact springs carried by said block, means including a plunger and a manually operable handle secured to said plunger for operating said contact set, said plunger passing through an opening in said block which intersects said top surface, a recess within said top surface for receiving said handle, said handle being of substantially greater width than the width of said block, whereby the top of said handle is substantially coplanar with said top surface when said plunger is depressed and said handle overhangs said side surfaces in order to facilitate manual operation of said contact operating means.
